ATTORNEY.

UNITED STATES PATENT OFFICE.

EUGENE E. KERN, OF ST. LOUIS, MISSOURI, ASSIGNOR TO WILLIAM R. ALBERTS AND HUBERT J. ECHELE, BOTH OF ST. LOUIS, MISSOURI.

SUPPORT.

Application filed March 21, 1928. Serial No. 263,323.

This invention relates to supporting devices and is illustrated herein as embodied in a device of a type adapted to support panels of relatively thin material by engagement 5 with the side edges of the material.

In the illustrated embodiment of the invention the support is shown as being so constructed as to support the adjacent side edges of two panels of glass and is of a type suitable 10 for use in connection with show windows, glass lamp shades and globes, and the like. A feature of the invention consists in providing a support of this type with resilient members which grip the side edges of the supported 15 panels and prevent them from vibrating.

Another feature of the invention consists in providing such a support that is devoid of solid fastenings. By virtue of such a construction there is obviated the liability of the 20 glass to break or crack as a result of undue pressure being exerted thereon by means of the solid fastenings. Furthermore, the supported panels may be quickly and easily removed from or inserted into the resilient 25 gripping members of the support without the necessity of first manipulating any fastenings.

Still another feature of the invention consists in the provision of a support of the character described that is simple in construction, 30 and may be manufactured economically and by the use of ordinary machinery. As illustrated, the support is pressed out of a single narrow strip of suitable material, and the strip is provided at each of its ends with a plurality of ears that may be used in securing the support in place.

Other features and objects of the invention will become apparent from a reading of the 40 specification in the light of the accompanying drawings, in which:

Fig. 1 is a plan view in section of a support of the improved type holding two panes of glass,

Fig. 2 is a view in side elevation of the support of Fig. 1 with the glass removed,

Fig. 3 is a view in rear elevation of the support, and

Fig. 4 is an enlarged diagrammatic view 50 showing the resiliency of the support.

As shown in the drawing the reference numeral 10 indicates a hollow body portion of the support that is formed by being pressed out of a flat strip of metal, and is finished on its outer surface to provide a pleasing appearance. For the purpose of gripping the edges of a plurality of panels 18, 18, the marginal edges of the strip are bent at 12, 12, inwardly in the direction of the center of the body portion to provide a plurality of side or 55 clamping walls 14, 14, and they are bent outwardly in a direction away from the center of the strip to provide an additional plurality of walls 16, 16, which cooperate with the inner walls in holding in place the supported panels. 60

The walls 16, 16, being formed of thin metal are resilient, and they are formed with a crease 20 extending throughout the greater portion of the length of each wall, and this 70 crease co-operates with the natural resiliency of the clamping walls in gripping the side edges of the panels and holding them against vibration. Furthermore it will be observed that the construction is free of solid fastenings and that the glass may be inserted readily in the support without going to the necessity of removing fastenings, or being subject to breakage through pressure applied by the 75 fastenings.

For the purpose of holding the support in place during the use thereof the outer walls 16, 16 are formed with ears 19, 19, at each end which extend in a direction at right angles to the longitudinal axis of the support and occupy an overlapping position relatively to each other. A fastener receiving aperture 20 extends through the overlapping ears 19, 19, and is utilized in holding the support in place during use. 80

While the invention is illustrated herein as embodied in a support provided with a plurality of oppositely disposed clamping channels, it is to be appreciated that the invention contemplates employment in other 85 similar forms of supports as, for example, those in which only a single channel is provided. Supports of this latter type may be used in holding in position the top or bottom edge of a plate glass window, etc. 95

Having thus described my invention what I claim as new and desire to secure by Letters Patent of the United States, is:

5 A support for a panel, comprising a body portion, resilient means carried by the body portion and formed integrally therewith for engaging a side edge of the panel, and means

comprising ears formed on said resilient means for use in securing the support in place during the use thereof.

10 In testimony that I claim the foregoing I hereunto affix my signature.

EUGENE E. KERN.
